UNITED STATES PATENT OFFICE.

THADDEUS F. BAILY, OF ALLIANCE, OHIO.

CONTINUOUS FURNACE.

Application filed January 2, 1925. Serial No. 153.

This invention relates to continuous furnaces, and more particularly to a recuperative type of furnace especially designed for annealing sheets and the like although 5 equally adaptable for many forms of heat treating or heating at intense temperatures and is susceptible of use not only for heating or heat treating metals but for burning brick or the like.

10 The objects of the invention are to provide means for continuously passing the material to be treated through a preheating chamber, a heated chamber and a cooling chamber communicating with each other in the order named, and passing gas over the material in the opposite direction to the travel of the material.

15 The above and other objects may be attained by providing an elongated hood or tunnel divided into three communicating chambers or compartments, the central chamber being provided with heating means, means being provided for passing the material to be treated continuously through the chambers and for circulating a gas through the chambers at the inlet and discharge ends of the hood or tunnel over the material in a direction opposite to the travel thereof, whereby the material is pre-heated in the 20 first chamber, brought to the desired temperature in the intermediate chamber and cooled in the third chamber, the pre-heating being accomplished by the gas circulating over the cooling material, and absorbing 25 heat therefrom and delivering the heat to the incoming material in the pre-heating chamber, while the cooling in the outgoing chamber is accomplished by returning the gas, which has been cooled in the pre-heating 30 chamber, to the cooling or outgoing chamber, auxiliary means being provided for further cooling the gas if desired before returning the same from the pre-heating to the cooling chamber.

35 Thus the material is pre-heated in the incoming or pre-heating chamber by waste heat absorbed from the outgoing material in the cooling chamber and also radiated from the walls of the heated chamber, the

additional heat necessary for bringing the 50 material to the desired temperature being supplied in the central or heated chamber by heating means, preferably electric resistors, and the cooling of the material being accomplished by returning the gases from 55 the pre-heating chamber to the outgoing or cooling chamber.

Means may also be provided for impinging the cooled gas upon the outgoing sheets immediately after they emerge from the 60 heated chamber in order to rapidly cool the material, as may be desired in some cases. In order to insure a reducing or non-oxidizing atmosphere within the furnace, and to compensate for leakage, a reducing gas or 65 oil suitable for creating a reducing gas may be injected into the heated chamber.

Especially in the process of annealing it may be desirable to rapidly heat the sheets up to nearly the desired temperature as they 70 enter the heated chamber and to then slowly bring the sheets to the desired temperature as they continue to pass through the heated chamber, and for this purpose the heated chamber may be divided into compartments 75 maintained at different temperatures.

An embodiment of the invention is illustrated in the accompanying drawing, in which,

Figure 1 is a longitudinal sectional view 80 through the improved furnace, and,

Fig. 2, a transverse section on the line 2—2, Fig. 1.

Similar numerals of reference indicate corresponding parts throughout the drawing.

The improved furnace comprises an elongated hood or tunnel indicated generally at 1, and provided in its central portion with a heated chamber or compartment 2, heated 90 as by the electric resistor troughs 3.

This heated chamber communicates on one side with the pre-heating chamber 4 and upon the other side with the cooling 95 chamber 5, the roofs of which are preferably inclined from the central heated chamber toward the ends of the hood or tunnel.

The material to be heated or heat treated

in the furnace is adapted to be continuously passed through the furnace, entering at the pre-heating chamber and passing through the same into the heated chamber, and then 5 through the cooling chamber. For the purpose of illustration, the drawing shows a furnace especially adapted for annealing sheets, and for this purpose endless conveyor chains 6 may be provided for continuously moving the sheets through the furnace, although any other well known conveying means is within the scope of the invention.

These conveyor chains are illustrated as 15 passing through longitudinal grooves 7 in the hearth 8 of the furnace, and provided with spaced fingers 9 arranged to support the sheets 10 above the hearth. The chains pass downward over sprockets 11 located 20 near each end of the furnace, one or both of which may be continuously driven in any suitable manner, the lower strands of the chains returning beneath the hearth, guide channels 12 being preferably provided for 25 supporting the same.

For the purpose of pre-heating the sheets in the chamber 4, a circulation of gas is maintained in the direction opposite to the travel of the sheets through the furnace, 30 the gas passing through a cooling chamber, and being impinged upon the outgoing sheets as by the baffle walls 13, and absorbing heat given off by the sheets; the gas then being carried around the wall of the central heated 35 chamber 2, and then, through the pre-heating chamber, in the direction of the arrows shown in Fig. 1, the baffle walls 14 in the pre-heating chamber serving to impinge the heated gas upon the sheets to pre-heat the 40 same.

It will be seen that the baffle walls in the pre-heating and cooling chambers divide the chambers into a number of compartments of some considerable height; the gas being retained for a period in each chamber, thus 45 increasing the efficiency of the apparatus in giving off its heat in the pre-heating chamber and absorbing heat in the cooling chamber.

As it is desirable to maintain a closed circuit of the gas to preserve a reducing or 50 non-oxidizing atmosphere within the furnace, a duct 15 preferably connects the entrance end of the pre-heating chamber with the exit end of the cooling chamber, a fan being provided in the duct as indicated at 16, to 55 create a circulation of the gas in the manner above described, returning the cooled gas from the pre-heating chamber to the cooling chamber to assist in quickly cooling the 60 sheets before they pass out of the furnace atmosphere.

In annealing sheets, it may be desirable in 65 some cases to rapidly cool the sheets as soon as they emerge from the heated chamber, and in order to accomplish the same a communica-

cation may be provided between the duct and the cooling chamber, at this point, as indicated at 17, a valve 18 being provided for controlling the same, whereby all or a part of the cooled gas may be returned to either 70 end portion of the cooling chamber as desired.

Doors 19, arranged to remain normally closed, are provided at the entrance and exit ends of the furnace to minimize leaking of 75 the reducing gas from the furnace. In the event it is desirable to further cool the gas from the pre-heating chamber before it is returned to the cooling chamber, auxiliary cooling means such as the cooling coils 20, 80 may be provided in the duct 15, preferably adjacent to the fan as shown in Fig. 1 of the drawing.

In order to insure a reducing or non-oxidizing atmosphere within the furnace, 85 and to compensate for leakage, a reducing gas, or oil suitable for creating a reducing gas, may be injected into the central heated chamber of the furnace as by the pipe 21.

Especially in the process of annealing, it 90 may be desirable to rapidly heat the sheets up to nearly the desired temperature immediately upon their entrance into the heated chamber, and to then slowly bring the sheets to the desired temperature as they continue 95 to pass through the heated chamber. For this purpose the heated chamber may be divided into compartments as by the partition wall 22, the compartments being maintained at different temperatures. As illustrated, 100 the small compartment 23 at the entrance end of the heated chamber may be maintained at a considerably higher temperature than the main body of the heated chamber, whereby the sheets are quickly brought 105 up to nearly the desired temperature as they pass through the compartment 23, after which they are more slowly brought to the desired temperature as they pass through the main portion of the heated chamber 2.

From the above it will be seen that the material to be treated is continuously passed in succession through a pre-heating chamber, a heated chamber and a cooling chamber, and a reducing gas circulated in the opposite direction over the material, pre-heating the incoming sheets with gas heated by the heat given off by the cooling sheets, while the sheets in the cooling chamber are cooled by returning the gas thereto from the pre-heating chamber, the sheets being cooled below a critical point before emerging from the furnace atmosphere.

Although the invention is illustrated and 125 described as designed for continuously annealing sheets, it should be understood that the furnace and method described are equally adaptable for many forms of heat treating or heating metals and other materials such as brick and the like.

I claim:

1. An annealing furnace comprising an elongated chamber, means for passing material continuously through the chamber, means for subjecting the material to a maximum temperature at an intermediate point in the chamber, means for passing a non-oxidizing or reducing gas through the chamber in the opposite direction to the travel of the material and means for returning the gas in a closed circuit to the opposite end of the chamber.
2. An annealing furnace comprising an elongated chamber, means for passing material continuously through the chamber, means for subjecting the material to a maximum temperature at an intermediate point in the chamber, means for passing a non-oxidizing or reducing gas through the chamber in the opposite direction to the travel of the material, means for impinging the gas upon the material and means for returning the gas in a closed circuit to the opposite end of the chamber.
3. A furnace including a pre-heating chamber, a heated chamber and a cooling chamber, means for continuously moving material through said chambers, and means for passing a non-oxidizing or reducing gas through the cooling chamber, around the heated chamber and through the pre-heating chamber in the opposite direction to the travel of the material.
4. A furnace including a pre-heating chamber, a heated chamber and a cooling chamber, means for continuously moving material through said chambers, and means for passing a non-oxidizing or reducing gas through the cooling chamber, around the heated chamber and through the pre-heating chamber in the opposite direction to the travel of the material and returning the gas in a closed circuit to the cooling chamber.
5. The method of annealing sheets or the like which consists in moving the sheets continuously through a pre-heating chamber, then through a heated chamber in which the sheets are first subjected to the maximum temperature, and then to a lower temperature substantially that desired in the sheet, and then through a cooling chamber.
6. A furnace of the character described including an elongated tunnel containing a preheating chamber, a heated chamber and a cooling chamber communicating with each other in the order named, means for continuously passing material through the tunnel, means for passing reducing or non-oxidizing gas through the tunnel in the opposite direction to the travel of the material, and means for maintaining the gas in a closed circuit and returning the same from the preheating chamber to the cooling chamber.
7. An annealing furnace including an elongated tunnel having heating means at a point intermediate its ends, means for continuously moving material through the tunnel in one direction and means for continuously circulating a non-oxidizing or reducing gas in a closed circuit through certain portions of the tunnel in the opposite direction to the travel of the material.
8. An annealing furnace including an elongated tunnel having heating means at a point intermediate its ends, means for continuously moving material through the tunnel in one direction and means for continuously circulating a non-oxidizing or reducing gas in a closed circuit through certain portions of the tunnel in the opposite direction to the travel of the material and for returning the gas to the opposite end of the tunnel in a closed circuit.
9. The method of annealing sheets or the like which consists in moving the sheets continuously through a pre-heating chamber, then through a heated chamber in which the sheets are first subjected to the maximum temperature, and then to a lower temperature substantially that desired in the sheet, and then through a cooling chamber in the presence of a reducing gas.
10. The method of annealing sheets or the like which consists in preheating the sheets, then rapidly bringing the sheets to nearly the desired temperature, then slowly bringing the sheets to the desired temperature.
11. The method of annealing sheets or the like which consists in preheating the sheets, then rapidly bringing the sheets to nearly the desired temperature, then slowly bringing the sheets to the desired temperature and then quickly cooling the sheets in a reducing atmosphere.
12. The method of annealing sheets or the like which consists in moving the sheets continuously through a heated chamber in which the sheets are brought to the desired temperature, then quickly cooling the sheets below a critical temperature, in the presence of a reducing gas, then slowly cooling the sheets below an oxidizing temperature.
13. The method of annealing sheets or the like which consists in moving the sheets continuously through a pre-heating chamber, then through an electrically heated chamber in which the sheets are first subjected to the maximum temperature and then to a lower temperature substantially that desired in the sheet, and then through a cooling chamber.
14. The method of annealing sheets or the like which consists in moving the sheets continuously through a pre-heating chamber, then through an electrically heated chamber in which the sheets are first subjected to the maximum temperature and then to a lower temperature substantially that desired in the sheet, and then through a cooling chamber.

chamber, in the presence of a reducing gas.

15. A furnace of the character described including an elongated tunnel containing a pre-heating chamber, a heated chamber, and 5 a cooling chamber, communicating with each other in the order named, means for continuously passing material through the tunnel, and means for passing gas through the tunnel in the opposite direction to the travel 10 of the material and for returning the gas to the opposite end of the tunnel in a closed circuit.

16. A furnace of the character described including an elongated tunnel containing a 15 pre-heating chamber, a heated chamber, and a cooling chamber, communicating with each other in the order named, means for continuously passing material through the tunnel, means for passing gas through the 20 tunnel in the opposite direction to the travel of the material, and means for maintaining the gas in a closed circuit and returning the same from the pre-heating chamber to the cooling chamber.

25. 17. A furnace of the character described including an elongated tunnel containing a pre-heating chamber, a heated chamber, and a cooling chamber, communicating with each other in the order named, means for continuously passing material through the tunnel, means for passing gas through the tunnel in the opposite direction to the travel of the material, means for maintaining the 30 gas in a closed circuit and returning the same from the pre-heating chamber to the cooling chamber, and means for cooling the gas before it is returned to the cooling chamber.

40. 18. A furnace of the character described including an elongated tunnel containing a pre-heating chamber, a heated chamber, and a cooling chamber, communicating with each other in the order named, means for continuously passing material through the 45 tunnel, means for passing gas through the tunnel in the opposite direction to the travel of the material, and depending baffle walls in the pre-heating and cooling chambers for impinging the gas upon the material, certain of said baffle walls having openings to permit a portion of the gas to pass therethrough.

55. 19. A furnace including a central chamber, an electric resistance element therein, a preheating chamber communicating with one end of the central chamber, a cooling chamber communicating with the other end of the central chamber, means for passing material continuously through the preheating, central and cooling chambers and means for transferring a cooling medium from the preheating chamber to the cooling chamber.

60. 20. A furnace including a central chamber, an electric resistance element therein, a preheating chamber communicating with

one end of the central chamber, a cooling chamber communicating with the other end of the central chamber, means for passing material continuously through the preheating, central and cooling chambers, means 70 for abstracting heat from the material in the cooling chamber and transferring it to the preheating chamber and means for transferring a cooling medium from the preheating chamber to the cooling chamber. 75

21. A furnace including a central chamber, an electric resistance element therein, a preheating chamber communicating with one end of the central chamber, a cooling chamber communicating with the other end 80 of the central chamber, means for passing material continuously through the preheating, central and cooling chambers, means for abstracting heat from the material in the cooling chamber and transferring it to 85 the preheating chamber, and means for maintaining a reducing or non-oxidizing atmosphere in all three of the chambers.

22. A furnace including a central chamber, an electric resistance element therein, a preheating chamber communicating with one 90 end of the central chamber, a cooling chamber communicating with the other end of the central chamber, means for passing material continuously through the preheating, central and cooling chambers, means for transferring a cooling medium from the preheating chamber to the cooling chamber, and means for maintaining a reducing or 95 non-oxidizing atmosphere in all three of 100 the chambers.

23. A furnace including a central chamber, an electric resistance element therein; a preheating chamber communicating with one end of the central chamber, a cooling chamber communicating with the other end of the central chamber, means for passing material continuously through the preheating, central and cooling chambers, means 105 for abstracting heat from the material in the cooling chamber and transferring it to the preheating chamber, means for transferring a cooling medium from the preheating chamber to the cooling chamber, and means for maintaining a reducing or non-oxidizing atmosphere in all three of 110 the chambers.

24. A furnace including a central chamber, an electric resistance element therein, a preheating chamber communicating with one end of the central chamber, a cooling chamber communicating with the other end of the central chamber, means for passing material continuously through the preheating, central and cooling chambers, and 120 means for circulating a reducing or non-oxidizing gas through the cooling chamber, then through the preheating chamber and returning the gas to the cooling chamber in 125 a closed circuit. 130

25. An annealing furnace including a pre-heating chamber, a heated chamber and a cooling chamber communicating with each other in the order named, means for continuously moving material through the pre-heating, heated and cooling chambers in one direction and means for continuously cir-
- culating a non-oxidizing or reducing gas in a closed circuit through certain of the chambers in opposite direction to the travel of 10 the material.

In testimony that I claim the above, I have hereunto subscribed my name.

THADDEUS F. BAILY.
